UNITED STATES PATENT OFFICE.

ERNST J. DAHLEN, OF CHICAGO, ILLINOIS.

HAIR CURLER.

Application filed March 21, 1925. Serial No. 17,216.

This invention, in general, relates to improvements in that class of devices commonly referred to as curling irons and more particularly to electrically heated curling irons. Specifically, I have reference to that type of curling iron which takes the form of a pair of tongs or jaws hinged together so that they can be closed upon the hair from one side for the purpose of gripping it. To those versatile and familiar with this particular art, it is well known that in employing curling irons of the above character, a wave in the hair may be produced in several different manners, depending upon the construction of the tongs or jaws of the curling iron proper. That is to say, if the jaws are regular in contour, the wave is usually produced by first gripping the hair and then twisting it around both of the jaws or tongs. On the other hand, if one of the tongs presents a convex surface towards the hair and the other a cooperating concave surface, the hair or other material therebetween takes an analogous shape when gripped between the tongs without the necessity of any twisting.

Now, I desire it understood, that although I have disclosed, as the preferred embodiment of my invention, a curling iron having a convex shaped jaw and a cooperating concave shaped jaw that my invention is not to be limited thereby, for it is equally well applicable to any type of curling iron. Furthermore, I do not desire my invention to be limited to electrically heated curling irons, for it may be applied to gas heated irons, as well as other types, without deviating from the features and principles of my invention.

An object of my invention is to provide an improved curling iron of simple, compact and inexpensive construction.

Another object of my invention is to provide a curling iron equipped with a yieldable swivel or hinge, to permit the swiveled end of one of the jaws to be moved away from the associated lower jaw.

A still further object of my invention is to provide a curling iron wherein the hair is gripped uniformly throughout the entire length of the jaws of the iron and to obviate the possibilities of the hair binding the jaws when placed between the jaws adjacent to the swivel.

In accordance with the general features of the present invention, there is provided a curling iron equipped with a pair of jaws or

tongs, the lower jaw presenting a convex surface to the hair and the upper jaw presenting a concave surface to the hair, yieldably hinged together. Resilient means is provided for urging the concave shaped jaw always into contact with the convex shaped jaw but permitting the swivelled end of the concave jaw to move upwardly when sufficient pressure or leverage is applied thereto.

In accordance with other features of the invention there is provided improved electrical connections for the curling iron to effect proper heating thereof.

Other objects and advantages of the present invention will more fully appear from the following detailed description taken in connection with the accompanying drawings which illustrate one embodiment thereof, and in which—

Figure 1 is a plan view of a curling iron embodied with the features of the present invention;

Figure 2 is a front elevation thereof showing in dotted lines one of the jaws in an open position;

Figure 3 is an enlarged central vertical section taken on a line 3—3 of Figure 1, and

Figure 4 is a sectional view taken on a line 4—4 of Figure 3 looking in the direction indicated by the arrows.

Referring now to drawings in detail in which like reference numerals designate similar parts throughout the several views 10 denotes a handle which may be made of any suitable material, preferably however, of a molded character. Each end of the handle 10 is equipped with a concentric circular aperture, both apertures being preferably in alignment. Molded in one of these apertures is a metallic sleeve 11 and molded in the other aperture is a metallic sleeve 12 (Figure 3). One end of a jaw or tong, which I shall hereinafter term a heating rod 13, is tightly fitted into the sleeve 11. The heating rod 13 constitutes the lower jaw of the curling iron and is of a convex contour. The heating rod 13 is stationary and is adapted to cooperate with a concave shaped movable jaw or tong 14 positioned thereover.

Positioned adjacent that end of the handle 10, in which the sleeve 11 is located, is a member 15 equipped with an aperture 16 through which one end of the heating rod 13 passes and is suitably secured thereto. The member 15 extends upwardly for a

short distance, and is equipped with a right angle lateral projection 17. The upper part of the member 15, including the lateral projection 17, is recessed to form a housing 5 for a spring 18. The spring 18 is secured at 19 to the upper part of the lateral projection 17. As clearly shown in Figures 3 and 4, the jaw 14 is equipped with an arm 20, comprising two legs 21 and 22 between 10 which the stationary heating rod 13 passes. The arm 20 projects downwardly and laterally from the jaw or tongue 14 and is at an obtuse angle with respect to the tong 14. The lowermost ends of the legs 21 and 22 15 are joined by a cross member 23, preferably knurled on its lower face. Integral with and projecting upwardly and laterally at about a right angle to the tong 14 is a bracket 24 comprising two legs 25 and 26. 20 Leg 26 is equipped with an aperture 27 near its upper end and leg 25 is equipped with an aperture 28 near its upper end.

The lateral projection 17 of the member 15 is equipped with a pair of legs 29 and 30, as shown in Figure 1, which telescope the bracket 24. Connecting the legs 29 and 30 is a pin 31 which is secured to the said legs. The ends of the pin 31 project into the apertures 27 and 28, respectively, from 30 the legs 26 and 25. The apertures 27 and 28 are larger than the diameter of the pin so as to permit the end of the tong 14 to ride up and down on the pin 31, as will be more fully explained hereinafter.

35 The primary portion of the spring 18 is secured at 19 to the projection 17. The spring 18 is extended into the space separating the legs 29 and 30 of the projection 17 and encircles the pin 31. The legs or ends 40 32 and 33 of the spring 18 extend downwardly from the bracket 24 along the inner wall of each of the legs 21 and 22, respectively. The ends 32 and 33 are secured 45 at points 34 and 35 to the legs 21 and 22, respectively. It should be noted that the ends of the spring are turned outwardly and then downwardly so as to completely clear 50 the heating rod 13 (Fig. 4). The part of the spring 18 encircling the pin 31 and extending downwardly shall be hereinafter referred to as the secondary portion of the spring. The spring 18 tends to at all times urge the lever arm 20 of the tong or jaw 14 into the position shown in Figure 3.

55 The stationary heating rod 13 is hollow so as to provide a casing or housing for the heating wires referred to generally by the reference numeral 40. The ends of the heating wires 40 terminate in the sleeves 41 and 60 42 which receive the end of the electrodes 43 and 44, respectively. The other end of the electrode 44 emerges in a central aperture 45 in the handle 10 connected to the aperture and the end of the handle. Fitted 65 in the sleeve 12 is a swiveled plug 46

equipped with a cap 47 threaded thereon. The cap 47 is provided with an opening 48 in which is secured a flexible conduit cord 49. The conductors 50 and 51 of the cord 49 are secured to terminals 52 and 53 by 70 suitable screws withing an opening 54' in the plug 46. Secured at one end to the terminal 53 and extending inwardly through the plug 46 into the aperture 45 is a central electrode 54 equipped with an enlarged 75 end 55 fitted in a bore 56 located inside of the handle. As best shown in Figure 3, the end 57 of the electrode 44 is normally in engagement with the end 55 of the electrode 54.

The inner end of the plug 46 is equipped 80 with an annular contact ring 60 and an annular groove 61 into which the end 62 of the electrode 43 projects, making contact with the ring 60. The contact ring 60 is connected by a wire 62' with the terminal 52. 85

The operation of my improved curling iron is as follows:

Normally as previously mentioned, the double acting spring 18 maintains the tong 14 and its associated lever arm 20 in the 90 position shown in Fig. 3. In order to separate the tong 14 from the stationary heating iron 13, the lever arm 20 is pushed forward from the handle 10 causing the integral tong 14 to be pivoted on the pin 31. 95 The hair to be curled is then inserted intermediate the tong 14 and the rod 13. Upon releasing hold of the lever arm 20, the tong 14 will be forced downwardly by the action of the spring 18. Now if it was not for the 100 movable fulcrum feature, the tong 14 in closing upon the rod 13 would tend to cause the hair therebetween to be pushed backwardly and the pressure would not be applied uniformly to the whole length of the hair. By 105 pushing upwardly on the arm 20, the spring 18 may be expanded and the tong 14 moved upwardly. The apertures 27 and 28 permit the end of the tong 14, formed into the bracket 24, to be moved upwardly about 110 the pin 31. This action will enable the tong 14 to be closed evenly and uniformly upon the hair. That is to say, the tong 14 will be substantially parallel to the heating rod 115 13 when being closed.

This type of a swivel or pivot is highly advantageous, inasmuch as it not only facilitates the handling of the curling iron, but its use also results in a far better looking wave in the hair, inasmuch as the pressure 120 is applied uniformly to the hair placed therebetween. This construction also minimizes the possibilities of the hair being caught at the pivot point of the tong and the heating iron and becoming burnt therefrom.

Also, the improved handle 10 of my curling iron, enables the stationary heating rod 13 and its associated tong 14 to be readily detached therefrom. The handle 10 may be 125 130

easily and quickly connected to any lamp or wall socket connection through the medium of the detachable swivel plug 46 and the associated cord 49. Then again, the handle 10 oftentimes becomes damaged or broken and it is desirable to replace it. Now, in my construction, by merely pulling the plug out at one end and the heating rod out of the other end, the handle is completely separated from the curling iron and a new one may be applied to replace it.

Now, I desire it understood that, although I have disclosed and described specifically one embodiment which I consider the preferred embodiment of my invention, the appended claims are the only criteria upon which the scope and breadth of my invention should be based.

I claim:

1. In a curling iron, a first gripping member, a second gripping member pivotally attached at one end to an end of the said first gripping member, resilient means encircling the pivot for permitting the pivoted end of the second gripping member to be moved away from the first member, and a lever member connected to the pivoted end of the second gripping member and extending to the opposite side of said first gripping member for spreading the pivoted ends of the said gripping members apart.

2. In a curling iron, a heating rod, a handle detachably mounted on the said heating rod in longitudinal alignment therewith, a concave shaped member pivotally attached at one end to an end of the said heating rod, a lever member integral with the pivoted end of the said concave shaped member and extending to the opposite side of the said heating rod for causing the pivoted end of the concave shaped member to be moved away from the said heating rod and resilient means associated with the concave shaped member on the side opposite that of the lever member for applying tension to the pivot of the heating rod and its associated member.

3. In a curling iron, a first gripping mem-

ber, a second gripping member pivoted at one end to the said first gripping member, resilient means connecting the said pivoted end of the said second gripping member to the said first gripping member for urging the pivoted end of the second member into contact with the first member, and a lever member integral with the said pivoted end of the second gripping member and extending to the opposite side of the said first gripping member adapted to counteract the urging tendency of the said resilient means and to space the pivoted end of the second gripping member from the first gripping member.

4. In a curling iron, a first tong member, a second tong member pivoted to one side of the said first tong member, an element integral with the said second tong member and extending to the opposite side of the said first tong member, the said tong members having a free floating pivot, the said element being movable to separate the tong members, and resilient means associated with the second tong member on the side of the first tong member opposite to that of the said element for tensioning the pivot in the separation of the tong members.

5. In a curling iron, a pair of tong members, a pivot between them, a spring associated with the pivot, and a connection between the spring and one of the tong members for enabling the spring to serve as a pivot about which one member is pivoted when moved away from the other.

6. In a curling iron, a pair of tong members, resilient means between the members serving as a pivot for enabling one of the members to be moved parallelly away from the other, and a pivot associated with the spring, for limiting the said parallel movement and about which one tong member may be moved angularly with respect to the other tong member.

In witness whereof, I hereunto subscribe my name this 18th day of March, 1925.

ERNST J. DAHLEN.
